The ornamental design for a pulsed electromagnetic field applicator base, as shown.

DESCRIPTION

FIG. 1 is a front perspective view of a pulsed electromagnetic field applicator base;

FIG. 2 is a back perspective view of the pulsed electromagnetic field applicator base of FIG. 1;

FIG. 3 is a front view of the pulsed electromagnetic field applicator base of FIG. 1;

FIG. 4 is a back view of the pulsed electromagnetic field applicator base of FIG. 1;

FIG. 5 is a top view of the pulsed electromagnetic field applicator base of FIG. 1;

FIG. 6 is a bottom view of the pulsed electromagnetic field applicator base of FIG. 1;

FIG. 7 is a left side view of the pulsed electromagnetic field applicator base of FIG. 1; and,

FIG. 8 is a front side view of the pulsed electromagnetic field applicator base of FIG. 1.

The broken lines in the drawings illustrate portions of the pulsed electromagnetic field applicator base that form no part of the claimed design.
